PUMP FOR CHEMICAL MATERIALS

Reuben L. Nelson, Casper, Wyo.

Application June 23, 1937, Serial No. 149,817

3 Claims. (Cl. 103—50)

The present invention relates to pumps for chemical materials.

More particularly the present invention relates to means for pumping materials likely to have corrosive effects upon metals. The invention will be described in connection with means for pumping water treatment chemicals into the feed water lines of steam boilers. It will be understood, however, as the description proceeds that the invention has a broader application. Means have been suggested for the purpose referred to, but according to applicant's observation these prior devices have not been satisfactory due to the constant maintenance requirements and due to the loss of chemical material due to leakage. Certain prior devices have involved a pump having a piston, but it has been impossible to keep the piston from leakage. Injectors and syphons have been suggested for adding chemicals to other liquids but not with much success.

An object of the present invention is to provide improved means for introducing chemical material into liquids in which means the effects of wear and corrosive action may be reduced to a minimum.

A further object is to provide means of the kind immediately above referred to in which the pumping of the chemical may be maintained for prolonged periods of time in correct adjusted proportion to the flow of liquid into which the chemical is to be introduced.

A further object is to provide an improved pump for chemicals having corrosive characteristics which is well adapted to meet the needs of commercial operation.

Further objects will appear as the description proceeds.

Referring to the drawings—

Figure 1 is a fragmentary view illustrating an embodiment of the present invention as applied to a feed water pump as commonly encountered in power plants. According to this figure the pump comprising the illustrated embodiment of the present invention is operated in response to pressure changes within the feed water pump.

Figure 2 is a fragmentary view showing an embodiment of the present invention as applied to a locomotive, the embodiment of the invention being operated in response to changes in steam pressure within the steam cylinders operating a feed water pump.

Figure 3 is a view in side elevation of a chemical pump embodying the principles of the present invention.

Figure 4 is a longitudinal sectional view of the structure shown in Figure 3.

Figure 5 is a sectional view illustrating a modification of a portion of the structure shown in Figure 4 whereby the stroke of the piston may be readily controlled.

Figure 6 is a diagrammatic view along the lines of Figures 1 and 2 but showing means for pumping fluid in contact with solid chemical substances.

Referring first to Figure 1, the numeral 10 indicates as a whole a pump for pumping chemicals. Said pump, for purposes of this description, may be considered to be made up of three integral parts, the operating section 11, the pump 15 section 12 and the intermediate packing gland section 13.

The numeral 14 indicates a water pump operated through the medium of the piston rod 15 by the steam cylinder 16. The two sides of the water pump 14 have connected thereto the pipes 17 and 18 connected to the two sides of the operating section 11 of the chemical pump 10. It will be understood that as the pressures vary at the two ends of the water pump 14, corresponding variations will be communicated through the pipes 17 and 18 to the two ends of the operating section 11.

The numeral 21 indicates an inlet pipe for raw water, which pipe 21 connects with the feed water heater 20. Pipe 19 admits water from the feed water heater 20 to the pump 14. The outlet pipe from pump 14 is not illustrated.

The numeral 22 indicates a tank for supplying chemical material to the pipe 21. For this purpose a pipe 23 is provided, which may be called a suction line, leading from the chemical supply tank 22 to the inlet side of the pump section 12 of the pump 10. A pipe 24, which may be termed a chemical discharge line, connects the outlet side of the pump section 12 to the pipe 21.

Referring now to Figure 2, a water pump is indicated by the numeral 25, which is operated from the steam cylinders indicated as a whole by the numeral 26. Water is taken into the pump 25 through the pipe 28 and is discharged through the water line 27. Just as in the structure illustrated in Figure 1, the chemical supply tank 22 has connected thereto the pipes 17 and 18. According to the structure shown in Figure 2, 50 said pipes 17 and 18 have pressures therein varying in accordance with the variation in the pressure within one of the steam cylinders 26. According to the structure shown in Figure 2, just as in Figure 1, the chemical supply tank 22 is 55

provided with the suction line 23 leading to the inlet of the pump section 11 and is also provided with the chemical discharge line 24 connected to the outlet of said pump section 11. Said chemical discharge line 24 connects with the water line 28.

Reference may now be had to Figures 3 and 4 for a description of the details of construction of the chemical pump 10. As indicated above, the 10 pump 10 may be considered as comprising three sections, the operating section 11, the packing gland section 13 and the pump section 12. Said sections are connected end for end to provide a unitary elongated device.

15 The operating section 11 includes a member 29 having the bore 30 for the reception of the piston 31. The outer extremity of the cylindrical member 29 may be reduced in diameter and may be externally screw-threaded for the reception of 20 the cap 32, which cap is provided with the axially disposed bore 33 for the reception of a pipe fitting providing juncture with the pipe 18. Said cylindrical member 29 at the other end of the bore 30 is reduced in diameter to provide the internal 25 shoulder 34 adapted to loosely receive the piston rod 35. The piston 31 should preferably have a floating relationship with the piston rod 35. In other language, the piston 31 should be so disposed upon the piston rod 35 as to permit a slight 30 rocking action without having any considerable play longitudinally of the piston rod 35. The purpose of this floating relationship will appear presently. Intermediate of the shoulder 34 and the bore 30 is a portion 36 of materially greater 35 diameter than the diameter of the piston rod 35. Disposed within the portion 36 is the collar 37 fitting freely within said reduced portion 36 and also fitting freely upon the piston rod 35. A setscrew 38 limits movement of the collar 37 in a 40 left-hand direction as the parts are viewed in Figure 4. Packing material 38 is disposed between the shoulder 34 and the collar 37. The portion 36 of the operating section 11 is provided with the threaded aperture 40 communicating 45 with the bore 30 at the region to the right of the piston 31 as the parts are viewed in Figure 4. Said threaded aperture 40 is adapted to receive a fitting for providing juncture with the pipe 17. The extreme right-hand extremity of the cylindrical member 29 is provided with the reduced 50 screw-threaded portion 41 for receiving the packing gland section 13.

The pump section 12 of the pump 10 includes the member 42 provided with the bore 43, which 55 bore receives the right-hand extremity of the piston rod 35 with an easy fit. The left-hand extremity of the cylindrical member 42 is provided with a reduced screw-threaded extremity 44 for receiving the packing gland section 13. 60 The right-hand extremity of the cylindrical member 12 is closed by means of the end member 45.

The cylindrical member 42 adjacent to its 65 right-hand extremity is provided with the threaded aperture 46 for the reception of the chemical suction line 23. For simplicity of manufacture, the chemical suction line 23 should 70 preferably communicate with the under side of the pump section 12. The aperture 46 provides a valve seat adapted to receive the valve 47, which in its biased position closes communication between the bore 43 and the suction line 23. Said valve 47 is illustrated in the form of a simple ball.

Disposed diametrically opposite to the aperture 75 46 is the aperture 48 for receiving the chemical

discharge pipe 24. The aperture 48 may be provided at its bottom with the valve seat 49 adapted to cooperate with the valve 50. Said valve 50 is illustrated in the form of a simple ball and is biased by gravity to closed position whereby to stop backflow of chemical from the discharge pipe 24 to the bore 43. It will be understood, of course, that when the ball valve 50 is moved out of its biased position it will permit flow of material from the bore 43 to the discharge line 10 24.

Referring now to the packing gland section 13, said section includes the member 51, internally threaded at its ends to receive the corresponding threaded extremities of the operating section 15 11 and the pump section 12. Said member 51 is provided with a grease gun connection 52 whereby lubricant may be charged into the interior of the packing gland section 13. Mounted in sliding relationship with the piston rod 35 20 are the two collars 53 and 54 adapted to ride within cylindrical pockets 55 and 56, respectively, of the corresponding ends of the operating section 11 and the pump section 12. Packing material 57 is provided within said pockets 55 and 56. Said packing material 57 is adapted to be compacted by said collars 53 and 54, and for this purpose a coil spring 58 is provided adapted to urge said collars 53 and 54 apart.

Inasmuch as chemical material is adapted to 30 be admitted through the suction line 23 and discharge line 24, said lines, together with the valves 47 and 50 and their cooperating parts including the pump section 12 and the piston rod 35, will 35 preferably be made of material strongly resistant to the corrosive action of the chemical being pumped.

Figure 5 illustrates means for conveniently adjusting the stroke of the piston 31. In Figure 5 the port 33 is disposed in the peripheral portion 40 of the cap 32. Disposed axially of said cap 32 is the setscrew 59 extending into the interior of the cylinder 11. Said setscrew may be locked in position by means of the lock nut 60.

As indicated above, Figure 6 illustrates a construction in which water is pumped through a container containing solid chemicals whereby to dissolve said chemicals and deliver them into a stream of water or the like.

According to the construction shown in Figure 6, one side of the water pump 25 is connected to one end of the cylinder 11 through the pipe 18. The other side of the water pump 25 is connected to the other end of said cylinder 11. Connected to the inlet side of the pump 25 is the suction line 61, and connected to the outlet side of the pump 25 is the discharge line 62, which may lead to a boiler (not shown).

The numeral 63 indicates a container for solid chemicals. Said container 63 may be provided 60 with the false bottom or screen 64 for holding said chemicals away from the bottom of the container 63. The suction pipe 65 connects the suction line 61 to the suction side of the cylinder 12. The discharge pipe 66 connects the discharge 65 side of the cylinder 12 with the upper portion of the chemical container 63. The discharge pipe 67 connects the bottom of the container 64 with the pipe 61 at a region more closely adjacent to the pump 25 than is the inlet pipe 65. A valve 68 is provided in the pipe 67 for preventing backflow of fluid through the container 63 from the discharge pipe 67.

The mode of operation of the described embodiments of the present invention will be clear 75

without detailed explanation. According to the structure shown in Figure 1, variations in pressure at the two ends of the operating section 11 of the pump 10 are produced in correspondence to the variations in pressure at the two ends of the water pump 14. According to the structure disclosed in Figure 2, the variations in pressure at the two ends of the operating section 11 are maintained in accordance with variations in pressure at the two ends of one of the steam cylinders which operates the water pump. According to the structure disclosed in Figure 6, variations in pressure at the two ends of the operating section 11 are maintained in accordance with variations in pressure at the two ends of the pump 25. In any case the operations of the pump 10 are in synchronism with the operations of the water pump whereby chemical will be supplied to the feed water in direct proportion to the operation of the pump which pumps the feed water. According to the system disclosed in Figure 6, water will be drawn from the suction line 61 when the piston rod 35 is drawn to the left. The valve 68 will prevent the suction of fluid into the container 63 at this time. When the piston rod 35 is moved toward the right, water will be delivered through the container 63 in contact with chemicals therein, past the valve 68 into the section line 61 forwardly of the inlet pipe 65. Chemical dissolved from the solids in the container 63 will be mixed with the water entering the pump 25 and will be forced out through the discharge line 62 to the boiler.

The piston 31 will be reciprocated within the bore 39 in a manner which will be clear without further explanation. The piston rod 35 will have a bearing within the packing material 57—57. By reason of the floating relationship of the piston 31 with respect to the piston rod 35, the piston rod 35 is free from thrust except in an axial direction. It will be preferred in practice to make the piston 31 readily separable from the piston rod 35, thereby simplifying the job of renewing either the rod or the piston when desired. Inasmuch as the only bearing for the rod 35 is in the packing material 57, the rod slides freely with a minimum of wear. The packing material 57, being compacted by the spring 58, is at all times maintained in proper packing relationship with the sliding rod 35 regardless of wear of said packing material. By reason of the lubricant which may be charged into the packing gland section 13 through the connection 52, the packing material is maintained in proper condition.

As the piston rod 35 reciprocates it will draw chemical material through the suction line 23 and discharge this chemical material through the discharge line 24. In other words, when the piston rod 35 is moved to the left as the parts are viewed in Figure 4, a suction will be set up within the bore 43, holding the valve 50 tightly to its seat but causing the opening of the valve 47 to suck in chemical material through the suction line 23. Upon movement of the piston rod toward the right, the valve 47 will be tightly seated and the chemical material will be discharged from said bore 43 past the valve 50 into the chemical discharge line 24 to be delivered to the feed water with which it is to be mixed. By reason of the fact that the valves 47 and 50 are disposed along the diameter of the bore 43 at the extremity thereof, the proper vertical lift of the chemical is had without exerting side pressure against said piston rod. The pump according

to the present invention does not require a particularly close fit between the piston rod 35 and the bore 43 inasmuch as the constantly compacted material 57 protects the device against passage of chemical to the left as the parts are viewed in Figure 4. In other words, the pump according to the present invention requires no fluid-tight metal-to-metal bearings in the chemical end of the pump. It will be understood that the invention is applicable for other purposes than that above mentioned, of forcing chemical into feed water and the like. For example, the device may be utilized for pumping lubricant if preferred. Another use to which the device has been put is the proportioning of chemicals into gasoline during its manufacture. Many other uses will occur to those skilled in the art.

Though certain preferred embodiments of the present invention have been described in detail, many modifications will occur to those skilled in the art. It is intended to cover all such modifications that fall within the scope of the appended claims.

What is claimed is—

1. In a device of the character described, a pump, said pump comprising an operating section, a packing gland section and a pump section all united together, said operating section having a cylinder, a piston within said cylinder, said pump also having a piston rod connected with said piston and packing material comprising a bearing for said piston rod and adapted to have a limited movement along said piston rod, said pump section of said pump also having a chamber the capacity of which is controlled by operation of said piston rod, said chamber having a valved port permitting ingress into said chamber while preventing discharge therefrom and another valved port permitting discharge from said chamber while preventing ingress thereto, and spring means for constantly urging said packing material to predetermined positions relative to said pump, said packing gland section being adapted to be filled with lubricant enclosing said piston rod.

2. In a device of the character described, a pump for pumping chemicals, said pump comprising an operating section, a packing gland section and a pump section all united together, said operating section having a cylinder, a piston within said cylinder, said pump also having a piston rod connected with said piston and packing material comprising a bearing for said piston rod and adapted to have a limited movement along said piston rod, said pump section of said pump also having a chamber the capacity of which is controlled by operation of said piston rod, said chamber having a valved port permitting ingress into said chamber while preventing discharge therefrom and another valved port permitting discharge from said chamber while preventing ingress thereto, and spring means for constantly urging said packing material to predetermined positions relative to said pump, part of said packing material being subject to changes in pressure within said operating section, said packing gland section being adapted to be filled with lubricant enclosing said piston rod.

3. In a pump for chemical material, in combination, an operating section including a cylinder having a piston slidably therein, fluid pressure means communicating with the two ends of said cylinder to cause reciprocation of said piston within said cylinder, a packing gland section secured to said operating section, said pack-

ing gland section including a pair of packing members adapted to have limited movement along said piston rod, spring means between said packing members for exerting a continuous compacting force against said packing members to move said packing members to predetermined positions relative to said pump, said packing members comprising a bearing for said piston rod, and a pump section secured to said packing gland section, said pump section including a cylinder

for receiving an extremity of said piston rod, said last mentioned cylinder being provided with a removable inlet valve assembly and a removable outlet valve assembly, said inlet valve and outlet valve assemblies being located in the extremity of said pump section opposite to said operating section and closely adjacent to said cylinder.

REUBEN L. NELSON.
